FILM VIEWER

Arthur J. Van Alstyne, Lancaster, N. Y.

Application October 22, 1949, Serial No. 5,651

Term of patent 7 years

(Cl. D61—1)

To all whom it may concern:

Be it known that I, Arthur J. Van Alstyne, a citizen of the United States, residing at Lancaster, in the county of Erie and State of New York, have invented a new, original, and ornamental Design for Film Viewer, of which the following is a specification, reference being had to the accompanying drawing, forming a part thereof.

Figure 1 is a front perspective view of the film viewer, embodying my new design. Figure 2 is a rear perspective view thereof.

I claim:

The ornamental design for a film viewer, substantially as shown.

ARTHUR J. VAN ALSTYNE.
